ELECTRON DISCHARGE POWER AMPLIFIER

Philip T. Smith, Princeton, N. J., assignor to
Radio Corporation of America, a corporation
of Delaware

Application June 29, 1948, Serial No. 35,756

44 Claims. (Cl. 250—27.5)

1

In this application, I disclose a new and improved electron discharge device of the screen grid type.

The ultimate objects of my invention are as follows: to provide an electron discharge device with more power output at frequencies of the order of 50 to 500 m. c.; to provide a high gain electron discharge device for operation at high frequency; to provide such a device which is adapted to be modulated over a very wide modulation frequency range such as used in television; to provide an electron discharge device which is adapted to be grid modulated and provides substantially linear grid modulation over a wide range of modulation frequencies such as used in television systems and to provide an electron discharge device having the features listed above, which device is easy to manufacture and is readily adapted to circuits for use thereof.

To obtain high frequency, high power outputs at reasonable anode voltages and to encourage smaller transit angles, higher current densities are required. This requires proper electrode shape and arrangement and field configuration. Further, when the transit times for all simultaneously emitted electrons cannot be made small, substantially equal transit times for simultaneously emitted electrons from various parts of the cathode surface are desired so that the upper frequency limit of operation at which normal electronic efficiencies may be obtained is not decreased. In addition, the electron emission must be formed into beams to reduce electron absorption by the control and screen grids, which absorption would increase the grid heating and cause undesired grid emission and would decrease the amount of useful current to the anode structure. Conventional beam forming electrodes complicate the electron discharge device structure, introduce undesired capacitance and inductance and aggravate tube electrode cooling problems.

A more specific object of my invention is to provide an improved cathode structure including an improved emission element and arrangement with improved beam concentrating elements, the electrode and element configuration and electronic fields produced thereby being such that the electron emission is of high density and highly directive.

An additional specific object of my invention is to provide a cathode and beam concentrating element, control grid, screen grid and anode arrangement with a field and electrode configuration such that the electron absorption by the control and screen grids is negligible.

2

High frequency operation requires small electrodes and leads and close spacing to reduce inter-electrode and lead capacitance and inductance and especially to limit the transit time of the electrons between the electrodes to a value which does not become an appreciable fraction of the operating period. However, close spacing increases inter-electrode capacitances and consequently the electrode area must be decreased and thus even with beam concentration and efficient operation in accordance with my invention, cooling becomes difficult in compact structures for high frequency, high power output.

A further specific object of my invention is to provide an electron discharge device of the screen grid type having small electrode dimensions (relative to the power output) short leads and close electrode spacing yet capable of large continuous power outputs at high frequency in which device critical electrode and lead capacitance and inductances are maintained at very low values.

An additional somewhat specific object of my invention is to provide new and improved apparatus and structure for cooling the cathode support, control grid, screen grid and anode structures and leads thereto and seals therefore to increase the power rating of the electrodes.

In high amplification of ultra high frequencies, and, in particular, push-pull operation at high frequencies, neutralization to prevent undesired capacitance feedback is a problem and short leads are required to minimize introduction of inductive reactance and the effects thereof. When two tubes of known screen grid type are operated side by side in push-pull operation, it is difficult to provide a connection of low impedance, at all frequencies, between the screen grids. Especially is this so where operation takes place at high frequency. Moreover, small differences in tube structure result in unbalanced push-pull amplifier systems.

An additional specific object of my invention is the provision of a push-pull electron discharge device structure which includes novel built in capacitors with short leads for neutralizing inter-electrode coupling, which device is substantially electrically symmetrical, per se.

A further object of my invention is to provide a push-pull electron discharge device of the screen grid type wherein the screen grid and cathode structure is compact and the impedance from screen grid to screen grid is low, the screen grids being tied together structurally.

An additional object of my invention is to provide a push-pull device of the screen grid type

having small dimensions and built in coupling capacitors between the grounded cathodes of the tetrode sections and the screen grids to insure low impedance therebetween.

A further object of my invention is to insure low impedance between the cathodes of the two sections by providing a cathode arrangement which in respect to the generated R.-F. currents acts as a single cathode.

An additional object of my invention is to provide a push-pull device which is suitable for amplifying high power of high frequency being especially useful in balanced push-pull amplifiers or modulators where freedom from self-oscillation is essential.

The electron discharge device of my invention is to be used as a modulated amplifier and a further object of my invention is to provide such a device for grid modulation wherein very high cathode emission densities are obtained and high percentage grid modulation may be carried out without causing noticeable amounts of grid current to flow on the positive cycle of the modulation currents. This improves the operating characteristics and reduces the electrode cooling problem.

Manufacture of an electron discharge device with compact closely related electrode structure is difficult and an additional object of my invention is to provide a device having precision parts which can be accurately constructed and easily assembled and lined up and in which alignment and spacing are rigidly maintained during operation thus minimizing change of electrical characteristics.

In describing my invention in detail, reference will be made to the attached drawings wherein Figure 1 illustrates symbolically the tube elements and connections of an electron discharge device arranged in accordance with my invention and included in a basic repeater circuit; Figures 2, 2a and 3 illustrate symbolically the electron emitting electrodes, electron control electrodes, screen grid electrode and anode and also illustrate the beam forming electrodes and the manner in which they concentrate the emitted electrons and guide them toward the anode and prevent them from reaching the control grid or screen grid in material amounts to be absorbed thereby; Figure 4 is a view transverse to the longitudinal axis of my electron discharge device partly in section to expose the general electrode structure and details of the anode electrodes and mounting and electrode cooling systems; Figure 5 is a view similar to that of Figure 4 but taken about at right angles thereto; Figure 6 is a plan view of the end of my electron discharge device showing the main header and the fluid cooling conductors and electrical conductors passing therethrough; Figure 7 is a sectional view transverse to the electron discharge device axis of Figure 5; Figure 8 is a perspective view of the cathode elements, beam focusing elements and control grid elements and supports for the same; Figure 8a illustrates details of the cathode support as viewed from the opposite side; Figure 9 is an enlarged elevation taken along the lines 9-9 of Figure 7. It shows details of the cathode mounting blocks, cooling circuits and electrical circuits therefore and the control grids and their mounts and cooling fluid and electrical circuits; Figure 10 is an exploded perspective view of the screen grids and the manner of mounting the same. This figure also shows details of a heat shield for the cathode and supporting means for

the control grid; Figure 11 is a perspective view showing the manner of mounting the neutralizing capacitors built into my improved electron discharge device structure for cross coupling the anodes and control grids; Figure 12 is an enlarged view of the relationship of the electrodes of my device. This view is taken along the lines 12-12 of Figure 7; Figure 13 is a section taken along the line 13-13 of Figure 5. This figure shows details of the cathode support structure; and Figure 14 shows in detail a support member between the cathode support structure and the control grid support to prevent movement of the control grid transverse to the longitudinal axis of my novel device.

Briefly, an electron discharge device made in accordance with my invention includes an evacuated envelope containing an electrode assembly comprising a two section cathode, two first or control grids, two second or screen grids, two anodes, beam focussing elements arranged adjacent the cathode elements of each cathode section with screen grid to screen grid, screen grid to cathode, and cathode section to cathode section coupling capacitors and neutralizing elements all combined and disposed within said envelope to form an internally neutralized device of the screen grid type with low impedance between the cathode sections and between the screen grids.

In Figure 1, I have shown by simplified basic wiring diagram using electrode and circuit element symbols, my novel tube in a push-pull repeater or amplifying circuit with an input transformer T and an output transformer T'. Reference will be made to this figure in the description which follows to explain the novel features of my invention. In Figure 1, the reference numerals or characters applied to the electrodes correspond to those used in the detailed description which follows in so far as possible. In this figure, it will be noted that coupling capacitors Csg are shown between both screen grids and the cathode structure. Coupling capacitors CK are also supplied between the cathode sections and neutralizing capacitors NC are supplied between the plates and control grids. The capacitors CK and Csg in series are between the two screen grids. All capacitors are built into the tube structure. Furthermore, the screen grids are directly connected together by lead 1 so that they are at the same R.-F. potential.

In order to provide an electron beam having high current densities and to permit the close spacing of the control and screen grids which is necessary for efficient high power operation, the electric field and electron configuration becomes important. In the practice of my invention, the electron field configuration at and near the cathode is as illustrated in Figures 2 and 2a of the drawings. The electric field is such as to form the electrons, leaving the cathode, into concentrated beams which are directed toward the anode. The electric field configuration is obtained by use of beam forming elements adjacent the cathodes operating at the cathode potential or if desired a potential negative with respect to the cathodes.

In Figures 2, 2a and 3, I have again used reference characters, to designate the elements, corresponding to the reference characters used in the detailed description which follows. In Figures 2, 2a and 3, 20 are the cathode elements and 30 are the focussing elements. In the tube structure there are a large number of cathode elements

20 in groups there being three or more groups as desired. The cathode elements of Figure 2 have flat emitting surfaces, those of Figure 2a are curved slightly as shown. The dash lines indicate the electron paths. The electric field near the electron emitting surface is such that the electrons leaving this surface are subject to a force which has a component directed toward a plane through the center of the emitting surface and perpendicular to it, this force component being greatest in the region of the edges of the electron emitting element. I prefer to utilize an arrangement as shown in Figure 3. In this arrangement, shown schematically, the cathode elements 20 comprise flat emitting surfaces interposed between the focussing elements 39 of similar shape parallel with and spaced from the cathodes. The surfaces of the focussing elements extend beyond the surfaces of the emitting cathodes. The first grids or control electrodes 22 are in line with the focussing elements as are the screen grid electrodes 25. The anode structure, not shown in this figure, is disposed beyond the screen grids and the electrons from the emitting surface follow parallel paths between the control and screen electrodes to reach the anodes. Similar but opposed electrode and beam guiding elements are also used in my push-pull electron discharge device.

An embodiment of my device is illustrated in the remaining figures of the drawings. This device comprises an electron discharge device closure member including as shown in Figures 4, 5 and 6, headers 10 and 10' separated by a cylindrical portion 12 as will be developed later. The envelope encloses a double cathode K, as shown in Figures 7, 8 and 8a, emitting electrons in opposite directions, electron beam focussing elements 39 associated with the cathodes, control grid elements 22 and 22' facing the cathodes and beam focussing elements, screen grid elements 25 and 25' facing the control grid elements and anodes 26 and 26' facing the screen grid elements.

The cathode K comprises three sections as shown in Figures 1, 8, 8a and 9 each of which sections are as shown in detail in Figures 8 and 8a with U-shaped cathode elements 20 spaced as shown. The control grid structure Cg and Cg', Figures 7, 8 and 9 comprises control grid elements 22 and 22' mounted close to the respective cathode sections. The novel screen grid structure Sg and Sg', Figures 7 and 10, comprising elements 25 and 25' are mounted close to the control grids. The anodes 26 and 26', Figures 4 and 7, are mounted facing the screen grid structures. Beam focussing elements 39 and 39' are carried by the cathode support being mounted between the cathode elements 20 which are U-shaped. The relationship of the elements is shown in Figure 12 which is an enlarged view on the lines 12-12 of Figure 7. The ends of all of the U-shaped cathodes are spot welded to a strip 32 on a main support 35, Figures 7, 8, 8a and 9. The ends of the remaining legs of groups (here 3 groups) of the U-shaped cathodes are spot welded to three strips 33, 33' and 33'', Figure 8a, on secondary cathode blocks 34, 34' and 34''. Note that in the sake of clearness, views of opposite sides of the cathode supports are shown in Figures 8 and 8a. The main support 35 is bolted to a lug L on the header 10 as shown in Figures 4 and 5. The electron focussing elements 39 and 39' and screen grid structure are also carried by this main support. This main support is also used to prevent transverse movement of the grid

electrode structure as described hereinafter. The control grids are separate and their structures are each supported by its cooling fluid pipes CP and CP' as shown in Figures 5, 6 and 7. These pipes are sealed into glass inserts in the header 10. Thus all of the electrodes, except the anodes, are supported by the main header 10 and all of the electrodes supported by the main header 10 are provided with cooling fluid conductors which are sealed in the header 10 and, with the exception of one cooling conductor for the cathode structures, are insulated therefrom so that the cooling fluid conductors also serve as electrical connectors.

The anode electrodes 26 and 26' are mounted on their cooling fluid pipes which are sealed into the header 10' as shown in Figures 5 and 6. The header 10' is adjustable as is the header 10 so that the anode electrodes may be moved relative to the other electrodes to establish mechanical and electrical symmetry between the anodes and screen grids.

The cathode structure, and beam focussing elements, control grids and screen grids and the supports for the same will now be described in detail. The cathode is in three sections and the sections being similar, one only will be described fully. An exploded view of the cathode and beam focussing elements and support and control grid are shown in Figure 8. These elements are mounted within the screen grid elements shown in detail in Figure 10.

The cathode comprises, as illustrated in Figures 8, 8a and 9, a plurality of U-shaped wire or strap-like elements 20 which may be of tantalum or the same coated with thoria or a matrix of tungsten-thoria. One leg of each of the elements 20 is spot welded to a supporting strip 32. The free legs of the cathodes are spot welded, in groups, to the strips 33, 33' and 33''. The strips 33, 33' and 33'' are bolted to liquid cooled support members 34, 34' and 34'' and the strip 32 is bolted to the liquid cooled main support member 35. The three members 34, 34' and 34'' are shown dotted in Figures 4 and 5 and in detail in Figures 7, 8 and 8a. The main support member 35 and support members 34, 34' and 34'' are separated and insulated from each other by a strip of mica. Thus members 34, 34' and 34'' are insulated from each other and member 35 except for the connections formed therebetween by the U-shaped cathodes. The capacitors formed between members 34, 34', 34'' and 35 permit the cathode sections to operate at the same A. C. potential since the impedance between the cathode sections has been reduced substantially to zero. The impedance between the individual cathode elements and between the same and the focussing elements and between focussing elements is extremely low because of the novel mounting used. The double structure operates as one structure with respect to alternating currents of high frequency. The advantage of such an arrangement in amplifiers is apparent.

The members 34, 34' and 34'' and 35 are bolted together by bolts 36. This structure is shown in detail in section in Figure 13 taken on the lines 13-13 of Figure 9. In the embodiment described there are three cathode assemblies each comprising a group of cathode elements support as described. There may be more groups or fewer groups of cathode elements depending on the number of phases of filament current to be used. Straps 33, 33' and 33'' are bolted to secondary cathode support members 34, 34' and 34''. There is a member 34, 34' and 34'' for each cathode sec-

tion and these members 34, 34' and 34'' are as described above bolted to the member 35 which is the main cathode and beam concentrating element support.

The members 32 and 33, 33' and 33'' also carry integral therewith or spot welded thereto the beam forming and focussing electrodes 30 and 30' of appropriate metal such as tantalum. These electrodes are run at the cathode potential and neither emit nor collect electrons. The focussing electrodes 30 and 30' are integral with the cathode blocks and are therefore cooled by the cathode support cooling fluid. They merely serve to direct the electrons and guide them toward the anode and away from the grid and screen grid as shown in Figures 2 and 3.

The main cathode support 35 extends beyond the members 34, 34' and 34'' as is shown clearly in Figures 4 and 5 and is fastened by bolts 38 to the main header support 10. The main support flange-like header 10 also seals the end of the electron discharge device. The envelope includes the metallic cylindrical member 12 with a flange 44 on the outer periphery thereof which is drilled and threaded for bolts 46 which cooperate with the ring 48 shouldered at 47 to bolt the main header 10 and member 12 together. To make a vacuumtight joint, a copper ring 50 is put between the bearing surfaces of the main heater 10 and cylindrical member 12. A cylindrical member 49 is used as a spacer between the outer peripheries of ring member 44 and member 48. The other end of the electron discharge device is closed in a somewhat similar manner. A ring 44' is welded or otherwise fastened to the outer periphery of member 12 and the ring member 44' is threaded to receive bolts 46' passed through a ring member 48' shouldered at 47' to engage the other main header 10'. To make a vacuumtight joint a copper ring 50' is inserted between the members 10' and 12. It will be noted that a very rugged tube structure has been provided and further that, as will be developed as the description progresses, the tube structure is easily built up and assembled.

Returning now to the cathode structure, it will be seen by reference to Figures 8a, 9 and 13 the cathode is in three sections and three phases of heating current are supplied thereto. The three cathode support blocks 34, 34' and 34'' each have fluid channels FC therein through which the cooling fluid may be circulated. The channels partly shown in said figure may be formed by drilling or otherwise and are connected by fluid conductors 60, 60' and 60'' (Figures 5 and 6), each including inlet and outlet pipes, to a source of cooling fluid not shown. The fluid conductors pass through three seals 62, 62' and 62'', Figures 4, 5 and 6, in the main base plate 10. In order to expose the member 35, lug L and bolts 38 and the metallic shield between the control grid and anode leads, described hereinafter, the fluid conductors 60, 60' and 60'' are shown in part only in Figure 4. The fluid conductors 60, 60' and 60'' also serve as electrical conductors of heating currents for the cathode member 20 and are insulated each from the other and from the member 35. The three seals 62, 62' and 62'' are similar and details of seal 62'' are shown in Figure 4. A steel cup 64 is welded into a circular opening in the header 10 and a Kovar cylinder 66 is welded to the cup 64 and/or header 10. A glass bead 68 is bonded to the Kovar member 66 and a Kovar end pipe 70 is bonded to the glass bead 68. The fluid conductors 60'' are then passed

through a metal plug 71 (Figure 6) which is welded into the end member 10. The mica sheet 37 insulates the filament support blocks 34, 34' and 34'' from the single filament support blocks 35. The bolts 36 pass through ceramic or glass rings 36', Figures 9 and 13, and washers 36'' of ceramic or the like material to prevent conductive coupling between members 34, 34', 34'' and 35 by way of bolts 36.

The main cathode support member 35 is also cooled by fluid in conductors 72 one of which is the fluid inlet, the other the fluid outlet. These fluid conductors shown in Figures 5, 6, 7, 9 and 10 are sealed in and conductively connected at 74, Figure 5, to the main base plate 10 and serve as the common cathode ground connection. In the embodiment illustrated, three phase heating currents are used and phases No. 1, No. 2 and No. 3 may be supplied from a source not shown, to leads 60, 60' and 60'', respectively. The use of three phase heating current reduces power supply hum.

It will be noted that the main support 35 is conductively connected to the main shell 12 of the tube, etc. and is at ground R. F. and D. C. heating current potential as illustrated in Figure 1. The members 34, 34' and 34'' and 33, 33' and 33'' and the ends of the cathode members 20 welded thereto are coupled to the member 35 and ground by the very large parallel by-pass capacitors formed between members 34, 34' and 34'', respectively, and the main support member 35. The capacitors found by these elements are shown by dotted lines in Figure 1. Thus the entire cathode structure is at ground radio frequency potential. This reduction of impedance between the cathode sections adds materially to the stability of operation of the tube structure in high frequency push-pull amplifying circuits.

The structure described above and hereinafter provides electronic circuit and mechanical advantages that are of particular significance when these structures are incorporated in amplifier tubes. I have provided liquid cooling of the mounting, supporting and lead in structures thereby reducing the thermal expansion enough to maintain the electrode alignment in normal operation substantially as established during assembly. The accurate alignment that can be obtained during assembly and retained during normal operation along with mechanical symmetry makes possible a grid to cathode and grid to screen grid capacitance balance between the two tetrode sections.

The control grid elements 22 and 22' are fastened to or made integral with their respective supports 21 and 21' as shown in Figure 8. These grids are rod-like elements of like length which fit tightly into holes of like depths drilled into the edges of supports 21 and 21'. It is to be remembered that with respect to electron emission from the cathode, the control electrode elements 22 and 22' are in line with the beam forming and guiding elements 30 and 30' to outline passageways for the electrons to pass from the cathode elements in concentrated sheets to the anodes. The grid members may be molybdenum and may be silver soldered or otherwise fastened to the edge of the supports 21 and 21'. The control grid base members 21 and 21' are supported by the concentric cooling fluid conductors CP and CP' to which they are fastened by soldering or otherwise as shown in Figures 7, 8 and 9. The fluid conductors CP and CP' in addition to acting as the inlet and outlet for the cooling fluid also

serve as electrical connections to the control grid electrodes and supports for these grids electrodes. The grid support and cooling fluid conductors CP and CP' are sealed into the header 10 as shown in Figures 5 and 6. This seal is quite like the seal 62" described above and will be described briefly. A cylindrical-like Kovar member 78 is welded to or otherwise fastened by a vacuumtight joint to the header 10. A glass member 80 is sealed to cylinder 78 and a Kovar member 82 is bonded to the glass member 80. The pipes CP and CP' pass through a vacuumtight plug like member in the end of member 80. It may be noted here that the grid electrodes are supported rigidly by the members CP, CP' and maintained in fixed closely spaced relation to the cathodes. In operation there may be some longitudinal movement of the grids and such is permitted. However, there is to be no transverse twisting or swaying of the grids and additional means to fix the grids in this respect will be described later.

The grid structure disclosed provides a sturdy mechanical support with accurate alignment and spacing of the elements is maintained during the normal operation of the device in which the grid is mounted. This is obtained by the effective cooling of the grid supporting pipes I provide and cooling of the attached glass seals which eliminates misalignment of the electrodes by thermal expansion due to energy absorbed at the control elements or power dissipated in the lead in and support pipes. The effective cooling of the supporting pipes provides a means of cooling the grid elements and thus prevents excessive electron emission from these elements. The element length is chosen relative to the element cross section so as to permit practically all of the power dissipated in the elements to be conducted to a coolant circulated in the supporting pipe.

The duplex screen electrodes 25 and 25' are mounted with good thermal and electrical contacts in rigid frame members shown in detail in Figures 7 and 10. These frame members comprise rigid strong side pieces 27, 27' and 29 and 29' fastened together by end pieces 85, 85' (at header 10 end) and 81 and 81' at the other end. The two framewise members are held in parallel relation by strong end members 89 and 89', which run the full length of the screen grids and hold the screen grid structures in parallel planes and prevent relative movement thereof in any direction. The side pieces 27, 27' and 29, 29' are shown in Figures 7, 10 and 13. The support 27, 27' and 29, 29' with end pieces 89, 89' is made as strong as reasonably possible to keep the electrode spacing fixed. The screen grid supports 27 and 27', are bolted to the main support member 35 by bolts 90 (Figure 13) passing through ceramic or the like sleeves 90' which insulates the bolts from the members 34, 34', 34" and 35. The members 27' and 29' are insulated from the members 34, 34', 34" and 35 by mica sheets 93 and 95.

The screen grid supports 27 and 27' and 29 and 29' have fastened thereto cooling fluid conductors 96 and 97 which extract heat from the screen grid supports. These fluid conductors take part in supporting the screen grid structure and this support taken with the frame members and supports described above include the screen grids in strong closed rectangular frame members with transverse spacer pieces 89 and 89' running the full length of the frame members to keep the exact spacing between the screen grid electrodes. The grid-like rods 25 and 25' are in two sections and are silver soldered in holes in the inner edges

of supports 27, 27' and 29 and 29'. The screen grid rods 25 and 25' extend from the said inner edges of the sides of the frame toward each other but do not meet. This structure is used to interrupt circuits at which undesired oscillations might be set up. The members 27 and 35 facing each other through the mica insulator 93 form a large capacitor between the screen grid electrodes 25 and the tube main support and cathode structure. The member 27' facing the members 34, 34' and 34" through the mica sheet 95 in series with the capacitor formed by members 34, 34', 34" and 35 forms a large capacitor between the screen grids 25' and the cathode and tube structure. The capacitors thus formed are shown by dotted lines in Figure 1. Thus the screen grids operate at substantially ground R. F. without using external by-pass capacitors and the stability of the device in high frequency circuits is enhanced.

The screen grids are cooled by fluid circulated in conductors 96 and 97' which as shown in Figures 5 and 6, feed into common conductors 98 and 98' as shown in Figures 5 and 6. These conductors 98 and 98' are sealed into a plug in a metal ring 99 such as Kovar which in turn is sealed into a glass member 100 in turn sealed into a metal, such as Kovar, ring 102 welded or otherwise fastened into the main header 10. This seal is similar to the seal 62" described above. These fluid conductors also serve as conductors for the A-C. and D-C. connections between the circuits and the screen grid electrodes, and are insulated from the main header 10 by the glass insert. Thus the screen grid, control grid and cathode and beam forming electrodes are all rigidly fixed with respect to each other and even though the distances between these electrodes are small, short circuits therebetween cannot take place.

Because of the novel construction of the screen grids and the arrangement and cooling thereof, I have provided circuit, thermal and mechanical advantages not known heretofore. Several circuit advantages accrue from the compactness and low impedance connections between elements and electrodes. Such low impedance paths are provided between the screen grid elements, between the two screen grid sections of a double screen grid tube, and between the screen grid structure and cathode. Of equal importance in ultra-high frequency amplifiers is the very short length of neutralizer element (described hereinafter) that is permitted when my structure is used. All of these features combine to provide excellent electrical stability in an ultra-high frequency duplex screen grid amplifier. The screen grid structure provides precision mounting and alignment of the elements which is unaffected by the processing temperatures and by normal operating conditions.

The anode electrodes 26 and 26' are similar and are mounted on opposite sides of the cathode elements 20 with collector surfaces A, Figures 4 and 6, very close to the screen grid electrodes. These electrodes shown in Figures 4, 5, 7 and 11 are made up of two blocks, 104 and 106 of metal. The blocks of metal are silver soldered to form vacuumtight joints. The blocks 104 and 106 have slots or channels or grooves in the face of one or both thereof to form fluid passageways through which the cooling fluid is forced. These passageways are part of the device envelope and the joints thereof are to be vacuumtight. One end of the anode proper terminates in a hollow metallic block 105 (Figures 4, 5, 7 and 11) into which a fluid conductor 107 is coupled. This block sup-

11

plies cooling fluid to the slots in the anode blocks 104 and 106. This fluid conductor and its continuation has several functions. In addition to being a fluid conductor, this conductor with continuations acts as a member of a tuning line connecting the anodes in a resonant circuit having low inductive reactance. The line 107 may be sealed into a glass insert 108 forming part of the wall of the electron discharge device. To facilitate bonding between the glass and line 107 the line may be of Kovar at 107" where it passes through the glass 108. The glass 108 is in turn sealed into a thimblelike member 109 of Kovar which is sealed into the header 10' by welding or the like. The member 109 is recessed so that cooling fluid may be fed therethrough by pipes 109'. The pipes 107 as constructed and sealed into the header 10' provide good strong supports for the anode electrodes. The members 107 also provide the electrical circuits for the anodes. The other end of the anode proper terminates in a hollow metallic block 111. The hollow block 111 has an opening therein into which an outlet pipe member 113 is coupled. This pipe is insulated from the electron collector block 104-106 throughout most of its length. The outlet pipe 113 passes through the block 105, into which it is sealed by a fluidtight joint, and extends within a metallic thermal insulating pipe 115 (Figure 5). The insulating pipe 115 extends within the outer conductor 107 and extensions thereof. The channel between the pipes 113 and 115 is closed at 117, i. e., about where this pipe enters the hollow block 105 and is terminated. Thus if cooling fluid enters between the pipes 115 and 113 there can be no flow therein since the path is closed at one end. The cooling fluid may be supplied as indicated by the arrows to the pipe 107 and taken from the pipe 113. The thermal insulating pipe 115 traps a liquid layer which acts to insulate the cooling fluid within the pipe 113 from that within the tube 107 and exterior to tube 115. This thermal insulation is obtained since the liquid trapped between pipes 113 and 115 has zero velocity with respect to the retaining pipe surfaces and there results a large temperature drop in the liquid-metal interfaces. The fluid inlet pipe 107 is continued through the wall of the tube forming part of a transmission line or anode tuning circuit. Member 107 forms one member of a parallel line and member 107' forms the other member of this line.

My anode as cooled permits an electron bombardment power input per unit area of bombarded surface in excess of 800 watts per square centimeter with a reasonable water flow and pressures not in excess of 70 pounds per square inch. By insulating nearly all of the return tube 113 from the anode block heat exchange between input and output coolant in the anode block is eliminated. The doubled walled pipe arrangement wherein the coolant is trapped insulates the input coolant from the output coolant. The liquid cooled anode header glass 108 to metal seals permits use of separate anode header seals which are, per se, cooled and are useful at high power levels and at high frequencies.

The electron discharge device electrodes as described supply considerable concentrated power in the form of electron beams originating at the U-shaped cathodes. The beams pass in concentrated sheets toward the anodes and considerable heat is generated. A shield 120, Figures 9 and 10, is interposed between the central portion of the U-shaped cathode elements 20 and the control

12

grid and screen grid supporting structures to prevent emission from the central portions of the cathode elements from reaching these supporting structures. Support members 122 and 122' are soldered to the main support 35 above and below, respectively, the members 34 and 34'. The member 122 (Figure 10) is reduced in size at 123 to form a shoulder that engages with the member 35 (Figure 9) to which it is soldered or otherwise fastened. A pin at 124 in the member 122 serves to locate the member properly during assembly of the electron discharge device. The member 122' (Figure 9) also has drilled therein a locating pin hole 124' and is fastened to the other end of the main cathode support member 35. The members 122 and 122' extend beyond the U-shaped cathode elements and are drilled at 125 and 125' as shown in Figures 9 and 10. The member 120 has end portions 120' and 120'' bent at right angles to the V-shaped main portion and these end portions are drilled to receive bolts which are threaded into the holes 125 and 125' in supports 120 and 122' to fasten the shield 120 rigidly between the cathode elements 20 and the control grid and screen grid supports including fluid conductors CP, CP', etc.

Since an object of my invention is to increase the power output of the electron discharge device, close electrode spacing is to be used. Thus the control grid and cathode are close together and precautions must be taken to prevent movement of these electrodes toward or from each other. The cathode and its support is so rugged that the chance of it moving out of alignment in operation is very slight. The same is true of the control grid support. However, the control grid support is not as rigid as the cathode support and pressure change in the fluid flowing in pipes CP, CP' might cause the grid structure to sway. The control grid electrode is therefore further stabilized with respect to later movement but is permitted to move slightly in a direction normal to the surface of the base plate 10. This bracing of the grid electrode against lateral movement is accomplished as follows. A mica member 130, Figures 9, 11 and 14 is bolted at one end to the member 122'. The bolts used to fasten the heat shield member 120'' may serve to fasten the mica element 130 to member 122'. The free end of the mica member 130 is split and one finger thereof is bolted to a support member 135 and the remaining finger is bolted in like manner to the support member 135'. Spacers 137 and 137' are placed between the mica member 130 and the members 135 and 135'. The ends of the control grid cooling pipes and supports CP and CP' are capped (fluid flow reversed) and the members 135 and 135' are welded, soldered or otherwise fastened to the ends of these pipes. This mica member as used insulates the control grids from the cathode support, yet prevents any lateral movement of the grids relative to each other or to the other electrodes of the device.

The electron discharge device of my invention includes built in neutralizing capacitors connected between the control grid of one of the device sections and the anode of the other section, and between the control grid of the said other section and the anode of said one section. These neutralizing capacitors are shown best in Figures 9 and 11. The control grid supporting pipes CP and CP' are terminated in caps at the ends remote from the main header 10 wherein the fluid is turned around to flow out. Members 135 and

135' are soldered, welded or otherwise fastened to the end caps of grid cooling pipe supports CP and CP'. The neutralizing capacitors 160 and 160' are fastened to these supports 135 and 135'. The members 135 and 135' extend outwardly in a direction parallel to a plane passed between the cathode emitting areas. The members 135 and 135' are drilled near the outer ends and the members 160 and 160' are bolted thereto. The members 160 and 160' extend in opposite directions from said aforesaid plane and then turn back and up at 161 and 161' to face a considerable area of the respective anodes 26 and 26'. These elements form the capacitors NC and NC' of Figure 1 and are dimensioned and adjusted to compensate and neutralize the capacity within the tube directly between the control grid and anodes. It will be noted that the beam focussing electrodes have not been included in the circuit of Figure 1. Omission thereof simplifies the circuits and permits better showing of the remaining elements and built in capacitors.

The electron discharge device of my invention is further adapted for stable operation in high frequency circuits by provision of a novel shield arrangement between the control grids and connectors CP, CP' and the anode and screen grids and their connectors. This shield is shown in Figures 4 and 6 and comprises side members 170 and 170' bolted to the respective screen grid frame members 85 and 85' (Figure 10). The side members extend in a direction parallel to a plane passed between the cathodes to a point beyond the control grid pipes CP and CP'. An end plate 172 is fastened between the ends of side plates 85 and 85' to completely block coupling between the control grid and its leads CP and CP' and the anode and screen grid and their connectors. The end plate 172 is trapezoidal to form a trapezoidal frame open at one end.

To facilitate assembly and adjustment of the tube characteristics, the header plates 10 and 10' are made adjustable. Then the cathode sections, their supports, the control grids, their supports, the screen grids, their supports and the fluid circuits and electrical circuits may be assembled and mounted on header plate 10. The anode electrodes and electrical and fluid circuits therefor may be assembled on the header 10'. The tube envelope is then assembled and the holes in the rings 48 and 48' are machined oversize so that the header plates may be moved slightly as desired to properly relate and space the electrode structures fastened to the two plates. The bolts 46 and 46' are then tightened to compress the copper gaskets 50 and 50' to make a vacuum tight joint between the headers 10 and 10' and the side walls formed by cylinder 12. The ends of cylinder 12 are rounded off and the copper gaskets 50 and 50' are each compressed between a flat surface (on plates, 40 and 40') and the rounded surfaces at the ends of cylinder 12. The spacer rings 49 and 49' prevent warping and deformation of the clamping rings 48 and 48' when pressure is applied. This novel adjustable header method of tube construction and assembly provides a practical method for the construction of evacuated devices requiring closely spaced elements. The double screen grid tube is such a device and the cathodes, grids, and screen grids may be conveniently aligned and spaced with the header plate 10 removed from the envelope. The anode structure on the header plate 10' may be handled in like manner. The adjustments provided permit accurate balance in spacing and capacitance

between the anodes and screen grid structures. An electron discharge device assembled in accordance with my invention is conveniently disassembled for repairs.

5 In an embodiment which operated well at a frequency of 100 mc/sec. the double cathode structure has a length of about 6.00", the active parts of the U-shaped cathodes are about 1" on each leg. There were 13 U-shaped elements in each of the three groups. The dimensions of each control grid, screen grid and anode are commensurate with the dimensions of the cathode structure. Each control grid is spaced about .050" from its cathode section. Each screen grid is spaced about .115" from its control grid and each anode is spaced about .167" from its screen grid.

20 The planar electron emitting surfaces of the cathode strips function to provide substantially equal transit times for electrons simultaneously emitted from various parts of said surface. This tends to increase the upper frequency of operation at which normal electronic efficiencies may be obtained. These strip cathodes also deliver substantial electron emission current densities with a minimum of magnetic modulation of the electron trajectories.

25 Because of the increased electron current densities that are utilized (of the order of 3 amperes per square centimeter at the cathode) and the decreased effective electrode spacings, the transit angle of the grid controlled amplifier tube is substantially decreased. It may be shown that:

$$35 \quad \theta = K \left(\frac{J}{S} \right)^{-\frac{1}{2}}$$

40 where θ is the transit angle, J is the electron beam current density and (S) is the effective spacing between the cathode and grid, this being the region of interest for transit angle considerations. These fields and configurations permit increased current densities and decreased transit angles making possible high frequency, high power outputs. In the embodiment described, the tube 45 operated well at 100 megacycles and an output of 50 kw.

45 I claim:

1. A cathode for providing a plurality of directed concentrated sheet-like beams comprising 50 a plurality of elongated emitting elements separated by spaces and an elongated non-emitting conducting element in each space, said non-emitting elements being detached from and extending beyond the emitting elements in the direction of said beams and a common conductive support connecting said emitting and non-emitting elements only adjacent ends thereof.

2. A cathode for providing a plurality of oppositely directed elongated electron beams along spaced paths comprising a beam focussing assembly having on opposite sides thereof parallel non-emitting conducting elements in a plane separated by spaces for receiving elongated electron emitting elements and an elongated electron emitting element disposed in each of said spaces said non-emitting elements being detached from said emitting elements, and conductive support means connecting said emitting and non-emitting elements only adjacent ends thereof.

3. An electron emitting structure including a main support in the form of a metallic strap-like member, a secondary support in the form of a metallic strap-like member insulated from said first member to form therewith a capacitor and 75 elongated cathode elements fastened at one end

to the main support and at the other end to the secondary support.

4. A cathode structure including a main support in the form of a rectangular metal bar, a secondary support in the form of a rectangular metal bar adjacent said main support and insulated therefrom to form therewith a capacitor, elongated cathode elements fastened at one end to the main support and at the other end to the secondary support, and fluid conducting channels cooperating with said supports for extracting heat therefrom.

5. A cathode structure comprising a main support in the form of a rectangular metal bar, a plurality of secondary supports in the form of similar bars of less length adjacent said main bar to form therewith capacitors, elongated cathode elements each fastened at one end to said main support and at the other end to a secondary support, there being groups of cathodes for each secondary support, and means for supplying multi-phase currents to said cathode elements comprising a common connection to said main support and separate connections to each of said secondary supports.

6. A cathode structure comprising a main support in the form of metallic strap, a secondary support in the form of a metallic strap insulated from said first strap to form therewith a capacitor, U-shaped cathode elements having one leg fastened to the main support and the other leg fastened to the other support, and beam focusing electrodes fastened to the main support and to the secondary support, said focussing electrodes being located between the legs of adjacent U-shaped cathode elements.

7. An electron beam emitting and beam focusing structure including a main support in the form of an elongated rectangular metal bar, a secondary support in the form of a similar elongated metal bar bolted to said first bar and insulated therefrom, a plurality of spaced cathode elements each having one leg fastened to said secondary support and the other leg fastened to said main support, focussing elements fastened to both supports in the spaces between the leg of said cathode members, and fluid conductors in said supports for extracting heat therefrom.

8. A cathode assembly comprising a pair of elongated oppositely disposed conductors, a plurality of U-shaped emitting elements in spaced registering relationship and having their ends secured to said conductors and elongated conductors positioned in the spaces between said U-shaped elements and having one end connected to said conductors.

9. An electron discharge device having within an evacuated container cathode elements, electron beam focussing elements separating the cathode elements, a common support for said cathode and beam focussing elements and fluid conductors for said support for extracting heat therefrom.

10. An electron discharge device having within an evacuated container cathode elements, electron beam focussing elements separating the cathode elements, a common support for said cathode and beam focussing elements, an anode electrode, a support therefore, a grid electrode interposed between said anode electrode and cathode elements, a support for said grid electrode and fluid conductors cooperating with each of said supports for extracting heat therefrom.

11. A double cathode structure comprising two support members of considerable surface area

facing each other through an insulating medium to form a large capacitor, electron emitting elements supported by each of said support members to emit two electron beams.

5. 12. A double cathode structure comprising two support members of considerable area facing each other through an insulating medium to form a large capacitor providing low alternating current impedances between these support members, a plurality of spaced electron emitting elements supported by each of said support members and a beam focussing electrode in each of the spaces between said emitting elements.

13. A double cathode structure comprising two support members of considerable surface area facing each other to form a large capacitor, and a plurality of U-shaped members with one leg of each U-shaped member fastened to one of said support members and the other leg of each U-shaped member fastened to the other of said support members.

14. A double cathode structure comprising two support members of considerable area facing each other through an insulating medium to form a large capacitor, a plurality of U-shaped electron emitting electrodes, said U-shaped members having one leg fastened to one of said supports and the other leg fastened to the other of said supports and being in spaced relation, and an electron focussing electrode in each of the spaces between said U-shaped members.

15. An electron discharge device comprising two support members of considerable surface area facing each other through an insulating medium to form a large capacitor, spaced electron emitting elements supported by each of said support members to emit two electron beams, beam guiding elements, in the spaces between said emitting elements, supported by said supports, a control grid element adjacent each cathode structure, two other supports of considerable surface area facing said first supports through insulating material to form therewith large capacitors, and screen grid elements mounted on said two other supports.

16. A push-pull electron discharge device of the screen grid type having electrodes including two cathode sections, a support for each therefor, two screen grids, a support for each therefor, and means for maintaining said cathode sections and screen grids at substantially the same alternating current potential forming capacitance between said supports.

17. An electron discharge device electrode structure comprising a metallic support, a plurality of elongated electrode elements fastened at one end to said support, fluid conductors cooperating with said support to extract heat therefrom, said elongated electrode elements being short enough so that the entire length of the elements is cooled by heat conduction along the element to the support.

18. A grid-like electrode for an electron discharge device comprising a frame member and parallel wire-like grid elements axially aligned and extending from opposite sides of said frame towards each other.

19. A screen grid structure comprising a frame with parallel side supports, elongated screen grid elements extending from said side supports toward each other in pairs to form in said frame a plurality of interrupted parallel conductors and a fluid and electrical conductor cooperating with said frame to extract heat therefrom and provide electrical connection thereto.

20. A grid structure comprising two rigidly spaced side members, and a plurality of elongated metallic elements extending from the side members toward each other to nearly meet.

21. A grid structure comprising two rigidly spaced parallel metallic side members, and a plurality of rod-like elements extending in spaced relation from each side member toward the other side member to nearly meet.

22. A double grid member comprising a first support comprising two rigidly spaced side members, a second support comprising two rigidly spaced side members, frame members for rigidly holding said supports in parallel planes and a plurality of elongated members extending from each side member of each support toward the other side member of each support to nearly meet in the space therebetween.

23. In an electron discharge device, a grid structure comprising a metallic picture frame-like member, a plurality of grid elements fastened to opposite inner peripheries of said frame-like members and extending toward each other to nearly meet, an envelope enclosing said grid structure and a support in said envelope for said grid structure.

24. In an electron discharge device, a grid structure comprising a metallic frame member, a plurality of grid elements fastened to opposite peripheries of said frame and extending toward each other to nearly meet, a cathode structure, an envelope for said grid and cathode structures, a support in said envelope for the cathode structure and a capacitor built into said support, one plate of said capacitor serving as a support for said grid structure.

25. In an electron discharge device, a double grid structure comprising two metallic frame members in parallel planes, metallic side pieces fastening said frames in rigid relation in said parallel planes, a plurality of rod-like elements extending from opposite inner peripheries of each of the frames toward each other to nearly meet, an envelope enclosing said structure and a support in said envelope for said double grid structure.

26. A cooled anode structure comprising an active surface and a fluid path adjacent thereto comprising an inlet pipe coupled to one end of said path, an outlet pipe coupled to the other end of said path and passing within said inlet pipe, and a fluid trap in the form of a second pipe surrounding said outlet pipe within said inlet pipe.

27. An anode electrode for an electron discharge device comprising a member having a plurality of parallel passageways extending therethrough, a tubular member connected to and supporting said anode, one end of said parallel passageways communicating with said tubular member and another tubular member within said first tubular member and communicating with the other end of said passageways.

28. An anode electrode for an electron discharge device comprising a hollow member having passageways extending therethrough, a tubular member connected to and supporting said anode, one end of said passageways communicating with said tubular member, and tubular means within said first tubular member and communicating with the other end of said passageways, said inner tubular means comprising a pair of members telescoped over one another.

29. An anode electrode comprising two metallic bars with complementary channels in the faces

thereof which are in register to form fluid channels, a hollow member at one end of said bars to complete a cooling fluid path to one end of said channels, a hollow member at the other end of said bars to complete a fluid path to the other ends of said channels, a fluid conductor coupled into said first hollow member and a fluid conductor coupled into said second hollow member and passing through said first hollow member and within said first-named fluid conductor.

30. An anode electrode comprising two rectangular elongated metallic bars having a plurality of longitudinal channels in one face of at least one thereof, said bars being joined together at said faces to form fluid channels which are vacuum-tight, a hollow member at one end of said bars to complete a cooling fluid path to said channels, a first fluid conductor coupled into said hollow member to complete a fluid path between the same and an external fluid source, a second hollow cap member at the other end of said bars to complete a fluid path to the other end of said channels, a second fluid conductor coupled into said last-named hollow member and passing through said first-named hollow member and within said first fluid conductor to form a second fluid path to said external source and a dead end conductor enclosing said second conductor within said first-named conductor to provide thermal insulation for said second named conductor.

31. An electron discharge device comprising an electrode envelope including a hollow member having an opening therein, a closure member for said opening, at least one electrode mounted in said hollow member, at least one other electrode mounted on said closure member and extending into the hollow member to be in electronically operative relation to said one electrode, and means for relatively adjusting the relative positions of said electrodes to establish symmetry of the device including means for adjusting the position of said closure member relative to the opening in said hollow member.

32. An electron discharge device comprising an envelope including a hollow member having an opening therein, a closure member for said opening, an anode electrode mounted in said envelope, electron discharge device electrodes including a screen grid mounted on said closure member and extending into the hollow member in electronically operative relation to said anode electrode, and means for relatively adjusting the relative position of said anode and screen grid to adjust the coupling therebetween including an adjustable joint between said closure member and hollow member.

33. In an electron discharge device, a hollow tube envelope having openings in opposite sides thereof, a closure member for each of said openings, an electrode structure mounted on each closure member and extending within said envelope to face each other in electronically operative relation, and means for adjusting the positions of at least one closure member relative to the opening closed thereby to adjust the relation of said electrodes said means including an adjustable joint.

34. In an electron discharge device, a hollow envelope member having openings in opposed walls thereof, a closure member for each opening, at least one electrode structure on each closure member and leads thereto extending through the closure member, said electrode structures each including an electrode extending

within the tube in electronically coupled relation to each other, and apparatus for fastening said closure members over said openings and adjusting the position thereof relative to the openings to change the electronic coupling between said electrodes.

35. An electron discharge device having an envelope including a header member, a cathode assembly supported from said header member, a screen electrode insulatingly supported from said cathode assembly and surrounding said cathode assembly, said header member having a plurality of apertures extending therethrough, and leads extending from said cathode assembly and through said header, and a lead extending from said screen electrode and through an aperture, and a control electrode positioned between said cathode assembly and screen electrode and having a lead supporting said control electrode from said header member and extending through another of said apertures, and a closure member for said header member for providing an envelope, an anode adjacent said screen electrode, and a lead extending through said closure member and supporting said anode.

36. An electron discharge device having an envelope including a header member, a cathode assembly and a screen electrode insulated from each other, said header member having a plurality of apertures therethrough, and a plurality of leads extending from said cathode, one of said leads extending through one of said apertures, and a lead extending from said screen electrode and through another of said apertures, and a control electrode positioned between said cathode assembly and screen electrode and having a lead supporting said control electrode from said header member and extending through another of said apertures, and a closure member for said header member providing an envelope, an anode, and a lead extending through said closure member and supporting said anode adjacent said screen electrode, said leads comprising tubular members and providing a transmission means for a coolant to and from said cathode assembly, electrodes and said anode.

37. In an electron discharge device, an envelope enclosing electrodes including a control grid, a support for said control grid including a coolant conductor sealed into said envelope, said conductor also serving as an electrical connection to said control grid, other electrodes in said envelope, electrical connections from said other electrodes passing through the wall of said envelope and a metallic shield supported by one of said other electrodes and extending between said grid support and said other electrodes and their electrical connections.

38. In a push-pull electron discharge device, an envelope having an opening therein to be closed by a header member, two anodes supported in said envelope, other electrodes including two control grids and two screen grids carried by said header and extending within said envelope in electronically coupled relation to said anodes, said header being adjustable relative to said opening to establish mechanical and electrical symmetry between said anodes and screen grids, and neutralizing capacitors within said envelope cross coupling said anodes and control grids.

39. An electron discharge device comprising an envelope enclosing electrodes including two anodes in the form of metal blocks with fluid channels therein, and supports for said anodes comprising parallel coaxial fluid conductors for each

anode extending through the envelope of said device, said coaxial fluid conductors serving to supply cooling fluid to and take cooling fluid from the respective anode blocks, said parallel coaxial conductors also serving as a part at least of a resonant circuit for said anodes.

40. In an electron discharge device, an envelope including a metal wall, a cathode structure on a cathode support carried by said metal wall and extending therefrom within said envelope, a grid structure on a grid support carried by said wall and extending therefrom to face said cathode in electronically operative relation, and a brace fastened between the ends of said supports remote from said wall to prevent relative movement of the grid and cathode structures.

41. In an electron discharge device, an envelope including a metal wall, a cathode structure on a cathode support carried by said metal wall and extending therefrom within said envelope, a grid structure on a grid support carried by said wall and extending therefrom to face said cathode in electronically operative relation, said cathode support and said grid support including metallic fluid conductors extending from the control grid through the envelope, said fluid conductors serving to extract heat from the cathode structure and grid structure and to form electrical connections thereto, and a brace fastened between the ends of said supports remote from said wall to prevent relative movement of the grid and cathode structures.

42. An electron discharge device having an envelope including a conducting header member, a cathode assembly and a screen grid assembly insulated from said cathode assembly, said cathode and screen grid assemblies being supported from said header member, said header member having a plurality of apertures therethrough, and a plurality of leads extending from said cathode assembly, one of said leads extending through one of said apertures and insulated from said header member, and a lead extending from said screen grid assembly and through another of said apertures and insulatingly sealed therein, and a control electrode positioned between said cathode assembly and screen grid assembly and having a lead insulatingly supporting said control electrode solely from said header member and extending through another of said apertures and sealed therein, and a closure member for said header member providing an envelope, an anode adjacent said screen grid assembly and a lead for insulatingly supporting said anode from said closure member.

43. An electron discharge device having an envelope including a conducting header member, a cathode assembly supported from said header member, a screen electrode insulatingly supported from said cathode assembly and surrounding said cathode assembly, said header member having a plurality of apertures extending therethrough, and leads extending from said cathode assembly and through said header, and a lead extending from said screen electrode and through an aperture and insulatingly sealed therein, and a control electrode positioned between said cathode assembly and screen electrode and having a lead insulatingly supporting said control electrode from said header member and extending through another of said apertures and sealed therein, and a closure member for said header member for providing an envelope, and an anode adjacent said screen electrode, and a lead ex-

tending through and insulatingly sealed in said closure member and supporting said anode.

44. An electron discharge device having an envelope including a conducting header member, a cathode assembly and a screen electrode insulated from said cathode assembly and said cathode assembly and said screen electrode being supported from said header member, said header member having a plurality of apertures therethrough, and a plurality of leads extending from said cathode, one of said leads extending through one of said apertures and insulated from said header member, and a lead extending from said screen electrode and through another of said apertures and insulatingly sealed therein, and a control electrode positioned between said cathode assembly and screen electrode and having a lead insulatingly supporting said control electrode from said header member and extending through another of said apertures and sealed therein, and a closure member for said header member providing an envelope, an anode, and a lead extending through said closure member and supporting said anode adjacent said screen electrode, said leads comprising tubular members

and providing a transmission means for a coolant to and from said cathode assembly, electrodes and said anode.

PHILIP T. SMITH.
